UNITED STATES PATENT OFFICE.

HENRY C. CHAMBERLIN, OF OLYPHANT, PENNSYLVANIA.

FURNACE-GRATE.

No. 873,411.

Specification of Letters Patent.

Patented Dec. 10, 1907.

Application filed September 14, 1906. Serial No. 334,618.

To all whom it may concern:

Be it known that I, HENRY C. CHAMBERLIN, a citizen of the United States, residing at Olyphant, in the county of Lackawanna and State of Pennsylvania, have invented new and useful Improvements in Furnace-Grates, of which the following is a specification.

This invention is a furnace grate, and has for its object to provide a grate-bar formed of a series of interlocking sections of novel construction, with means for connecting and spacing them so as to permit the use of fine fuel and to provide for a copious supply of air.

In the accompanying drawings, Figure 1 is a side elevation of the grate-bars. Fig. 2 is a side elevation of one of the grate-bar sections. Fig. 3 is a longitudinal section of one of the grate-bars showing the manner in which the sections are connected and spaced apart.

Referring specifically to the drawings, the grate-bars comprise a plurality of sections, each of which has a thin upstanding body part 5 and a horizontally extending fuel support 6 at the top which is also wider than the main portion of the section and is offset laterally on one side only of the section. Near the top and bottom of the body part 5 are openings 7 and 8, respectively, which receive rods 9 and 10 for connecting the sections, and on one side of the section are bosses 11 which extend around the openings 7 and 8 on the side of the section on which the fuel support is offset. Near their outer ends the bosses are reduced in diameter as at 12, which form shoulders 13. The reduced portions of the bosses of one section enter the openings in the adjacent section, and the shoulders 13 serve to space the sections from each other by engaging the side of the adjacent section as shown in Fig. 3. Additional means for spacing the sections and holding them in a straight line, are projections 5a adjacent the front and rear edges of the section on the same side thereof as the bosses. The ends of the connecting rods 9 and 10 are threaded to receive securing nuts 14 which are seated in recesses or counter-sinks made in the heavier and wider end sections 15 of the grate-bar which also have integral journal sleeves or projections on the outer sides thereof, through which the rock shaft extends.

In each grate-bar is a section provided with a downward extension 16 to which is

attached a link 17 which connects the grate-bars so that they will be rocked simultaneously. The link 17 will be connected to a suitable shaking lever.

The grate-bar herein described rocks or swings on a shaft 18 extending through registering openings 19 in the sections. The ends of the shaft will be secured in any suitable manner in the supporting frame of the grate. If desired the end sections of the grate-bar can be formed with trunnions for supporting the bar. In this case the shaft 18 will be dispensed with, which reduces the weight of the grate and provides for a copious supply of air to the grate through the openings 19.

The manner in which the sections are connected enables them to be set close together thus forming a grate in which fine fuel can be used, and at the same time providing for a sufficient supply of air to the grate, having free access between the body portions of the sections. As the sections are connected at two points they will be held in perfect alignment and relative movement thereof is effectively prevented.

I claim:

1. A grate bar comprising a plurality of transverse, interlocking sections, each section having an upstanding body part and a horizontally extending fuel support offset laterally from one side only of said section, tubular projections on the side only of the sections whence the fuel supports are offset for spacing them apart and interlocking them, and tie-rods passing through the tubular projections.

2. A grate bar, comprising a plurality of transverse, interlocking sections, each section having an upstanding body part and a horizontally extending fuel support offset laterally from one side only of said section, a tie-rod passing through the body parts and tying the sections together, and spacing projections on the same side of the body parts as the fuel supports to interlock and to space the sections apart so as to leave narrow air spaces between the supports and wider spaces between the body parts.

3. A grate bar comprising a plurality of transverse interlocking sections, each section having an upstanding body part and a fuel support projecting horizontally therefrom, the outer sections being wider than the intermediate sections and provided on their outer sides with counter-sinks and integral journal projections, tie rods passing through the

- body parts of the sections and having retaining members seated in the counter-sinks, said body parts having spacing projections to space the sections apart so as to leave narrow air spaces between the supports and wider spaces between the body parts.
4. A grate bar comprising a plurality of transverse interlocking sections, each section having an upstanding body part and a fuel support projecting horizontally therefrom, and the outer sections having tubular journals integral therewith and counter-sinks above and below the journals, tie rods passing through all the sections and having retaining members seated in the said counter-sinks, tubular spacing and interlocking projections on the body parts in line with the counter-sinks, perforations through the intermediate sections in line with the journals, and auxiliary spacing projections abreast of the perforations in the body parts.
5. A grate bar comprising a plurality of

transverse interlocking sections, each section having an upstanding body part flat on one side and a horizontally-extending fuel support offset laterally from the opposite side thereof, said fuel supports being wider in the direction of the axis of the grate bar than the body parts are thick, so as to leave narrow air spaces between the fuel supports and wider spaces between the body parts of the sections, tie rods passing through the body parts of the sections and tying them together, and interlocking and spacing projections extending from the side of the body parts on which the fuel supports are offset.

In testimony whereof I have signed my name to this specification in the presence of two subscribing witnesses.

HENRY C. CHAMBERLIN.
